SHOT SHELL

Walter L. Finlay, Fairfield, and Gilbert E. Hutchinson, Bridgeport, Conn., assignors to Remington Arms Company, Inc., Bridgeport, Conn., a corporation of Delaware

Application August 2, 1944, Serial No. 547,696

4 Claims. (Cl. 102—42)

1

This invention relates to ammunition, particularly to paper body shot shells, and contemplates a shot shell of improved ballistics and superior stability.

In the drawings:

Fig. 1 is a sectional elevation of a shot shell including the improved wad column of the invention and a crinkled skirted base wad.

Fig. 1a is a sectional elevation of the shot shell of Fig. 1 but provided with an alternative 10 end closure.

Fig. 2 is a fragmentary sectional elevation of a shot shell comprising an alternative embodiment of the invention.

Fig. 3 is a sectional elevation of the paper body of a shot shell showing another alternative embodiment of certain features of the invention.

Fig. 4 is a perspective view of a base wad partially formed from laminations of crinkled paper.

Shot shells as ordinarily manufactured comprise a metallic cap or head into which is inserted a tubular paper body that has been heavily impregnated with a moisture-repellent material, usually paraffin wax. A base wad, which may be of wound paper of suitable properties or other desirable material appropriately processed, is firmly pressed into the tube adjacent the head, and serves to join the head and body and to shield the relatively thin metal of the head from the high pressures developed in firing. A battery cup including a primer is pressed into a suitable aperture in head and base wad. An appropriate charge of propellant powder is placed in the shell adjacent the head, and filler wads including a cardboard over-powder wad are placed over the powder, separating the powder from the shot charge which occupies the forward part of the shell. One method of closing the open ends of such shot shells is to insert a cardboard top wad, having a diameter substantially equal to the interior diameter of the body into the shell over the shot charge, and to crimp the end portion of the body over such top wad by turning or rolling a short section thereof inwardly and back through 180°, so that the end of the inturned portion or roll crimp rests on the outer surface of the top wad. A preferred method of closing is illustrated in the patent to Finlay et. al. No. 2,242,907, May 20, 1941. According to this method, the end portion of the body is creased and turned inwardly and itself forms a flat closure integral with the body, which closure is subsequently sealed by affixing thereto an exterior sealing disk. Shot shells closed in this manner do not utilize a top wad, and hence give better patterns than shot shells closed by means of the more conventional top wad and roll crimp, for the reason that in shot shells of the latter construction, hereinafter

5 termed roll crimp shells, the top wad is ejected from the gun barrel in the same substantially perpendicular relation thereto which it has in the shot shell and hence tends to obstruct the forward movement of the central portion of the shot mass, deflecting the shot laterally and producing ring or blown patterns. On the other hand, the flight of the shot charge of a shell having an integral end closure, hereinafter termed 10 a flat top shell, is unobstructed and unimpeded by a top wad and hence produces superior patterns.

15 The present invention is the result of efforts to further improve the ballistics of shot loads and particularly the shot loads of flat top shot shells.

20 It has long been believed that leakage of powder gas past the filler wads which separate the powder charge from the shot charge is a factor not only in producing blown or ring patterns but in "leading." The latter term refers to the adherence of particles of lead to the gun bore. Poorly fitted or poorly constructed filler wads are believed to permit the escape of substantial quantities 25 of hot powder gas past the wad column and into the shot charge, producing shot turbulence and a certain amount of fusion which causes small particles of lead to be abraded or fused off from the shot and to adhere to the gun bore. It has also been reasoned that poor or 30 blown patterns are produced by the leakage of gases past the wad column causing a scattering of the shot charge. While these possibilities have been known and recognized in a somewhat 35 academic way, their full importance has not been appreciated prior to the present invention.

25 In the development of the present invention, it was discovered that the dispersion of the shot charge of a roll crimp shell is due primarily 40 to the presence of the top wad moving forwardly in advance of the shot charge and obstructing its flight; and this phenomenon was the more marked as the gas sealing properties of the wad column were increased. It was subsequently 45 found that in roll crimp shells optimum patterns were produced when a wad column was used which permitted the escape of gas for the reason that the escaping gases effectively displaced the relatively light cardboard top wad from the path of the shot. It must be concluded, 50 therefore, that a certain amount of gas must be permitted to escape past the wad column of the roll crimp type of shot shell to avoid spread patterns. Gas leakage is undesirable, since it 55 causes barrel leading, and, if excessive, tends to scatter the shot. The present invention contemplates a greatly improved wad which is both gas sealing and cushioning, and is especially adapted, though not limited to shells closed with- 60 out a top wad.

2

Where a close pattern is not a consideration as, for instance, when a scattered shot charge is desired, a wad column having improved gas sealing properties may be used to advantage in the roll crimp type of shell, as shown in Fig. 1a. Heretofore, scatter loads for producing open patterns have been made by embedding cardboard baffles in the shot charge for scattering the shot and these baffles have resulted in the production of much confetti and other debris which is of great annoyance to the shooter. Such baffles also separate the shot into distinct groups, with gaps between groups. However, as pointed out above, by using a wad column of improved gas sealing properties in a roll crimp shell, the shot will be effectively and uniformly scattered by the top wad alone and with a substantial reduction in confetti over known types of scatter loaded shells.

Filler wads of wad columns may be made from some form of hair felt, such for example as the felt described in the patent to Burghardt, No. 1,724,338, August 13, 1929; or may be molded from a suitable composition of fibrous and/or granular materials, as described in the patents to Woodford, No. 2,026,765, January 7, 1936, and Ernst, No. 1,659,649, February 21, 1928. The material and/or configuration of the wad column must be so chosen that the column as a whole has a certain amount of compressibility. The necessity for this arises from the fact that a comparatively heavy mass (1 to 1 1/4 oz.) of lead shot must be set in motion. Upon ignition of the powder the pressure rises very rapidly, and if the wad column does not yield to a certain extent during the initial movement of the shot mass, excessively high and somewhat dangerous powder pressures are developed, and the resulting hammer blow applied to the stationary shot mass will cause severe shot abrasion, deformation, excessive leading and poor patterns.

In one aspect, the present invention contemplates a filler wad column so prepared as to furnish both an improved gas seal and a yieldable pressure-transmitting cushion. To this end, a relatively porous and compressible wad, such as a wad of the type shown in the patent to Woodford, is impregnated with a medium adapted to quite completely fill all voids and interstices therein, and having lubricating properties. Appropriate impregnants are high melting point waxes of animal, vegetable, mineral or synthetic origin. Suitable waxes for wad impregnation may include such petroleum derivatives as the higher melting point paraffin waxes and the products commercially known as "Barnsdall wax" and "Scony 2300," the latter being a microcrystalline petro-latum wax; hydrogenated animal and vegetable derivatives with melting points higher than 120° F. such as hydrogenated soy bean oil, hydrogenated cottonseed oil, and the waxes commercially known as "Armour #1" and "Armour #2;" and synthetic wax-like materials, prominent among which are the "Santo" waxes. By "melting point" it is meant to define the point at which the wax has melted to a degree which permits significant amounts to run or migrate from the body of the wad. A lubricating wax which will not run into the powder at temperatures below 120° F. is suitable.

Although other fibrous felts structures of suitable strength may be used, a wad of the type shown in the Woodford patent is highly suited to this application by reason of its non-laminar felting characteristics. As pointed out in the Woodford patent, a characteristic of many felted

articles is the laying of the fibers parallel to the initial supporting surface with the resultant tendency to cleavage under stress. The random fiber orientation achieved in the practice of the Woodford process serves to reinforce the wad and to completely prevent laminar separation. When such a fibrous felted structure has been completely impregnated, as discussed in the preceding paragraph, it combines in one body the characteristics of strength, plasticity and lubricating effectiveness necessary to permit the elimination of the usual overpowder wad of heavy cardboard.

As set forth above, it has been found undesirable to impregnate the entire wad column, by reason of the fact that wads thoroughly impregnated are substantially incompressible and tend to produce high pressures. Pressures become excessive and patterns are undesirably scattered when more than about 90% of the entire filler wad column is impregnated. On the other hand, when less than about 10% of the wad column is impregnated, gas leakage becomes excessive. The requirements of commercial practice indicate that the impregnated portion of the wad column should be between 30% and 70% thereof, the remainder being unimpregnated.

A preferred form of wad column is one comprising two superposed wads, the lower wad being thoroughly impregnated with one of the aforementioned hardening and lubricating waxes and the upper wad comprising any conventional unimpregnated compressible material. The upper wad may be provided with the conventional rim lubrication. It will be understood, however, that the wad column may comprise other than two wads, as, for example, a single wad the lower portion of which is thoroughly impregnated with a high melting point wax; or three or more superposed wads, the impregnated portion of the wad column being 30% to 70% of the height of the column. Moreover, it will be noted that the preferred wad column does not include the usual cardboard over-powder wad which has been deemed necessary to prevent break-up of the soft filler wads, and itself disintegrates into an undesirable cloud of small particles.

Wad columns constructed in accordance with this invention have superior gas sealing properties as a consequence of which shot charge turbulence has been substantially eliminated with an accompanying reduction of barrel leading to as low as 1/20 that which has characterized the best gas sealing wad columns heretofore known. Moreover, the superior gas sealing properties of the impregnated wad column obviate the loss of energy due to gas leakage, and enable desired pressures and velocities to be secured with smaller powder charges. Moreover, by eliminating the cardboard over-powder wad, the potentially troublesome paper particles or confetti are substantially reduced.

As heretofore stated, the conventional shot shell as manufactured for the market in this country comprises a body of wound paper. To secure additional strength as well as for moisture proofing, the paper body is heavily impregnated with a wax such as paraffin wax. Commercial shot shells may be stored for substantial periods at temperatures such as to substantially soften the body impregnate and cause a part of such impregnate to flow into the contents of the shell including the powder. The effect of such migrated wax on the powder is definitely detrimental and the present invention contemplates the use, in conjunction with the improved wad column

heretofore described, of suitable devices for protecting the powder charge from the body wax.

Various means for powder protection are illustrated in the drawings. The shot shell of Fig. 1 comprises the conventional metallic head 10 containing the battery assembly 11 and receiving the end portion of the wax impregnated paper body 12. The body contains a charge of propellant powder 13 and superposed thereon a wad 14 impregnated as heretofore described. Upon the impregnated wad 14 is placed a rim-lubricated wad 15 of any conventional deformable material. The wads 14 and 15 may vary somewhat in thickness to provide the desired ratio of impregnated portion to unimpregnated portion. Above the wad 15 is the usual shot charge 16 preferably held in place by a closure 17 integral with the body 12 and sealed by a disk 18 adhering thereto.

The base wad 20 is of improved construction comprising an elongated circumferential skirt 21 adapted to extend up the wall of the body 12 sufficiently high to enclose the entire powder charge.

The base wad is preferably rolled from a strip of paper which is crinkled or otherwise provided with corrugations, as shown in Fig. 4, so that the completed wad will have an elasticity comparable to the elasticity of the body of the shot shell. By providing a base wad having an elasticity comparable to the elasticity of the body of the shell, localized splitting of the wad when under high gas pressures and especially at low temperatures is substantially eliminated thereby obviating rupture of the body of the shell. The skirt of the base wad may be formed in situ during the heading operation by using a punch of somewhat less overall diameter than the diameter of the wad, thereby allowing several plies of the wad adjacent the body of the shell to remain uncompressed.

The base wad and skirt are preferably of a relatively dry and somewhat pervious material, and hence the skirt 21 provides a medium for absorbing such wax as may leave the juxtaposed portion of body 12 under high temperature storage, thus preventing such wax from reaching the powder 13. The wax impregnate of the wad 14 superposed on the powder charge 13 has a relatively high melting point (above 120° F.) and hence will not flow into the powder even under the most extreme storage conditions. As an alternative construction, the base wad and its skirt may be properly treated by coating or impregnating with a suitable wax impervious lacquer varnish or similar medium of high melting point to insulate the powder from the migratory body wax.

Fig. 2 illustrates another means of shielding the powder charge from body wax. The shell comprises wads 14 and 15, similar to those described in conjunction with Fig. 1, and a base wad 25 having any desired powder contacting configuration. A nipple 26, which is preferably a short section of a dry fiber or paper tube, is fitted within the body 12 and extends from the end of the circumferential portion of base wad 25 to the adjacent face of filler wad 14. Such nipple 26 provides a medium for absorbing body wax when necessary and preventing movement of such wax into the powder. Although a paper tube has proven satisfactory, a tube comprising any suitable wax impervious material may be used.

Fig. 3 illustrates a shot shell body so prepared as to prevent the migration of wax into the powder without the use of such a separate shielding medium as is shown in Figs. 1 and 2. To the

inner surface of the portion of the shell body which contacts the powder, between the top of the base wad and the face of the impregnated filler wad 14, there is applied a coating 28 of a wax impervious lacquer varnish or other suitable medium. The shell body so prepared is assembled with the other components of a shot shell in the usual manner.

The powder protecting devices shown will be understood to be illustrative only. By means of the combination of impregnated and non-impregnated filler wads and powder shielding devices, shot shells, particularly flat top shot shells having high power loads, have been produced which consistently show excellent patterns and acceptable maximum pressures, both when fresh and after storage under very severe conditions. Moreover, when fired these shells produce substantially no confetti and relatively little or no leading.

What is claimed is:

1. A filler wad column positioned between the shot charge and the powder charge of a shot shell comprising a compressible cushioning portion seated against the shot and a piston portion seated against the powder, said piston portion comprising a fibrous felted body substantially completely impregnated with a waxlike lubricating material which will not run at temperatures below 120° F.

2. A filler wad column positioned between the shot charge and the powder charge of a shot shell comprising a compressible cushion wad seated against the shot and a piston wad seated against the powder, comprising a fibrous felted body substantially completely impregnated with a waxlike lubricating material which will not run at temperatures below 120° F.

3. A filler wad column positioned between the shot charge and the powder charge of a shot shell comprising a compressible cushion wad seated against the shot and a piston wad seated directly against the powder, said piston wad comprising a fibrous, non-laminar felted body substantially completely impregnated with a waxlike lubricating material which will not run at temperatures below 120° F.

4. A filler wad column positioned between the shot charge and the powder charge of a shot shell comprising a compressible cushion wad seated against the shot and a piston wad seated directly against the powder, said piston wad being not substantially less than 30% nor more than 70% of the height of the entire wad column and comprising a fibrous felted body substantially completely impregnated with a waxlike lubricating material which will not run at temperatures below 120° F.
